UNITED STATES PATENT OFFICE

127,824

DESIGN FOR A MASSAGE INSTRUMENT

Fahmy Garas, Cairo, Egypt

Application March 28, 1940, Serial No. 91,305
In Great Britain October 19, 1939

Term of patent 14 years

To all whom it may concern:

Be it known that I, Fahmy Garas, a subject of the King of Egypt, residing at 66 Ibrahim Pacha Street, Cairo, Egypt, have invented a new, original, and ornamental Design for a Massage Instrument, of which the following is a specification, reference being made to the accompanying drawing, forming part thereof.

I claim:

The ornamental design for a massage instrument, as shown.

FAHMY GARAS.
